(57) **CLAIM**

The ornamental design for a skid plate, as shown and described.

DESCRIPTION

FIG. 1 is a front right elevated perspective view of a skid plate showing our new design, the broken line showings of the vehicle being for illustrative purposes only, and forming no part of the claimed design.

FIG. 2 is a right front elevated perspective view of the skid plate design of FIG. 1.

FIG. 3 is a top plan view of the skid plate design of FIG. 1.

FIG. 4 is a front view of the skid plate design of FIG. 1.

FIG. 5 is a bottom view of the skid plate design of FIG. 1.

FIG. 6 is a right side view of the skid plate design of FIG. 1; and,

FIG. 7 is a left side view of the skid plate design of FIG. 1.
